2,572,673

MACHINE FOR MAKING CORNER MOUNTS

George Stokinger, Wakefield, Mass., assignor to
 Ace Art Company, Reading, Mass., a corpora-
 tion of Massachusetts

Application October 2, 1947, Serial No. 777,452

7 Claims. (Cl. 93—1)

1

This invention relates to machines for making mounting corners for photographs, cards, and the like, and has for an object to produce such corners from a pair of elements cut from two strips of stock, one, a cap element, having adjacent corners folded toward each other and secured to the flat face of the other or base element cut from the other strip. Such a corner mount is well adapted to have the cap element formed of transparent material such as cellophane, though it is not limited to the use of such material.

One object of the present invention is to provide mechanism by which the cap element is firmly held while it is severed from the cap strip and folded in position to be secured to the base element.

A further object is to provide simple and effective means for removing the completed mount from the machine.

Still another object is to provide a machine in which the corners of the cap element are folded into slightly overlapping relation so that there is no space therebetween for the passage of adhesive which might contact with the photograph or other element to be held thereby during use of the mount.

Further objects of the invention are to provide improved actuating mechanism for the various operating parts whereby the various functions of the machine are performed accurately and rapidly.

Further objects and advantages will appear from a description of an embodiment of the invention shown in the accompanying drawings in which

Figure 1 is a front elevation of the upper portion of a machine embodying the invention.

Figure 2 is a fragmentary view partly in side elevation and partly broken away and in section on the forward portion of the machine.

Figure 3 is a horizontal sectional view on line 3—3 of Figure 1.

Figures 4 to 7, inclusive, are detail sectional views on the correspondingly numbered section lines of Figure 3.

Figure 8 is a detail sectional view on line 8—8 of Figure 7.

Figures 9, 12 and 13 are views similar to a portion of Figure 7, but showing parts in different portions of the cycle of operations of the machine.

Figures 10 and 11 are detail sectional views on lines 10—10 and 11—11, respectively, of Figure 9.

Figure 14 is an exploded perspective view of

the two elements of which the mount is composed.

Figure 15 is a perspective view of a completed mount.

5 Referring to the drawings at 1 is indicated the platform of a press by which the parts of the corner mount are cut and secured together. This platform or table 1 is supported on suitable legs 2 and has upstanding therefrom frame 10 portions supporting for vertical reciprocatory motion a punch plunger 4. The upper end of this plunger 4 is connected by a pivoted connecting rod 5 to a crank arm 6 carried by a horizontal shaft 7 having at one end a suitable driving means such as a belt pulley 8 and a fly wheel 9. To the lower end of the plunger 4 may be secured a punch, which by the rotation of the shaft 7 is vertically reciprocated and is effective to punch a base strip from a strip of material 20 and apply it to the folded-in corners of a cap strip as will later appear.

The mechanism for feeding and supporting the relatively narrow cap strip 10 (see particularly Figures 3 and 8 to 13) is carried by the table portion 1. The cap strip 10 is relatively narrow and may well be of transparent material such as thin cellophane, though it is not restricted to any particular material. It is fed to the operative mechanism of the machine by the feed mechanism shown best in Figure 8, and which includes a lower smooth feed roll 11 which projects up through a slot 12 in a supporting plate 13 over which the strip 10 passes. By reason of the slot 12, the periphery of the roll 11 is 35 brought up to engage the under face of the strip 10.

Cooperating with this roll 11 to feed the strip is a top feed roll 14 carrying a feed cam element 15. This element 15 may be pivotally supported 40 at its forward end as on the pivot 16, and its opposite end may be pressed outwardly from the periphery of the roll 14, as by a spring 17, the parts being so arranged that when the cam 15 is downwardly positioned with reference to its supporting shaft 20, the cam 15 presses the strip 10 against the roll 11, and by so engaging the strip 10 therebetween it is fed forward intermittently by rotation of the cam 15. During the time that the cam is out of engagement with the strip 10, this strip is held against retrograde motion by means of a pivoted dog 25 having a foot portion 26 normally pressed against the strip 10 as by a leaf spring 27. Any tendency of the strip 10 to be pulled backwardly acts to tighten 50 the grip of the dog 25 thereagainst, clamping

it firmly to the plate 13, but any motion in the forward direction merely swings the dog 25 forwardly out of clamping engagement. The strip 10 is held against endwise motion between intermittent feeding actions by the clamping finger 28 which extends through a suitable opening in a guide plate 29, this finger being rocked into or out of contact with the strip 10 by a cam mechanism which will later be described.

Since the cam 15 occupies but a portion of the circumference of the roll 14, this feed of the strip 10 is intermittent, being accomplished only during that part of the revolution of the shaft 20 that the cam 15 engages the strip. This strip is thus fed intermittently forwardly, bringing its forward end portion over an anvil plate 30 (see Figures 7, 8 and 10). This anvil plate 30, which is stationary, has a pair of angularly related upstanding edges 31 and 32, the angular relation being 90°, but the strip 10, the forward end of which is at right angles to its length, passes over these walls 31 and 32 to the forward edge of the anvil plate 30. The edges 31 and 32 thus cross diagonally beneath the strip 10 substantially from one side to the other thereof.

Overlying the anvil plate 30 is a spring presser plate 35, which as shown best in Figure 7, is secured as by a rivet 36 at its rear end to the anvil plate 30. Its forward end terminates in a pair of angularly related edges mating the upstanding walls 31 and 32 of the anvil plate and spaced inwardly therefrom sufficiently for the material of the strip 10 to pass up therebetween. At the back edge of the anvil plate 30 is positioned a cutting knife 37 (see Figures 3, 6, 8 and 10).

After each intermittent feed of the strip 10 over the anvil plate, the knife 37 is actuated by a cam 38 (see Figures 3 and 6) carried by a rotary shaft 39. This cam acts upon a follower roll 40 pivoted within a slot 41 at the rear end of the knife 37, this knife being fulcrumed on the pivot pin 42. The piece of the strip 10 thus cut off lies between the anvil plate 30 and the presser plate 35 as shown in Figure 7 at 45 and immediately the forward end of the presser plate 35 is depressed by the action of a presser foot 46, forcing the central portion of the piece 45 down between the upstanding walls 31 and 32, as shown in Figures 9 and 11, thus lifting adjacent corner portions 47 and 48 of the piece 45 into the position shown in Figure 11 between the edges of the presser plate 35 and the walls 31 and 32. These corner portions 47 and 48 extend substantially throughout the length of the cut piece. With the parts in this position, a folder 50 having its forward end cut to present a pair of right angularly related inwardly extending edges 51 and 52 (see Figure 10) is moved laterally from the position shown in Figures 9 and 10 to the position shown in Figure 12 across the upstanding edges 47 and 48, folding the corners down over the presser plate 35. By positioning one of the edges 51 or 52 slightly in advance of the other, one of the corners 47 or 48 is folded inwardly of the other. The top member is thus folded into the form shown for the cap element A of Figure 14 with its side edges 55 and 56 in overlapping relation, the cap element now being held on the forward end of the presser plate 35. This foot 46 which depresses the forward end of the presser plate 35 from its normally slightly elevated position is shown in Figure 7, and is at the inner end of a lever 60 fulcrumed on the pivot pin 61 (see Figures 3 and 7) the outer end of the

lever having journaled in a slot 64 therein a follower roll 62, which is actuated by a cam 63 carried by the shaft 39.

The motion of the folder 50, as shown best in Figures 3 and 7, is produced by a cam 70 (see Figure 7) fixed to a shaft 71. This shaft 71 rotates in the direction shown by the arrow and at suitable times an arm 72 thereon impinges on a lug 73 upstanding from the outer end of the folder 50 and pushes this folder forwardly to effect the folding operation. As the arm 72 continues its rotation and slips by the lug 73 it engages one arm 74 of a dog 75 fulcrumed on the shaft 76 and rocks this dog in a direction to bring a second arm 77 of this dog against the inner face of the lug 73, causing this lug 73 to be pushed backwardly, retracting the folder 50.

As there is sometimes a tendency for the folded cap element A to become caught in the apex between the folding edges 51 and 52, a spring finger 78 may be provided having an up-turned inner edge portion 79 lying within the apex between the edges 51 and 52. In the retracted position of the folder, this end 79 is pressed up into a slot 81 in a plate 82 which forms the cover for the guideway in which the folder 50 is slidably guided in the position shown in Figure 12. In the positions of Figures 9 and 13, it is allowed to spring downwardly, dislodging the cap element should it have become caught in the folder.

The shaft 71 which actuates the folder also carries a cam 85 (see Figure 4) which acts on a follower roll 86 pivoted in a slot in the outer end of the finger 28, this finger 28 thus being actuated by the cam 85. The shaft 71 on its rear end carries a spiral gear 88 meshing with a similar gear on the shaft 89. This shaft 89 is connected through a pair of mating spiral gears 90 with the shaft 39 and also has fixed thereto a gear 92 which drives the feed shaft 20 through an idler gear 93 and a gear 94 fixed to the feed shaft 20. The shaft 89 also carries a spiral gear 97 which meshes with a spiral gear 98 on a vertical shaft 99 which is connected through meshing spiral gears 100 with the drive shaft 7.

While the cap element A is retained on the end of the presser plate 35, a base element having an activated adhesive coated portion is presented to the folded-in corners 55 and 56 and secured by the adhesive thereto. The base elements are punched from a strip 110 shown best in Figure 8. This strip 110 is positioned above the strip 10 and passes down over a guide bar 111 fixed to the machine frame at its rear end and down to and through a slot 112 of a punching anvil 113. It may be fed forwardly intermittently by pawl and ratchet driven feed rolls 119 (see Figures 1 and 2) actuated by a crank 1190 and connecting rod 1191 from the main drive shaft 6.

As shown best in Figures 9 to 13, the slot 112 in the anvil is formed between a base member 114 and a top member 115 superposed thereon and provided with a thickened portion 116 which bears directly against the member 114 and lifts the remainder of the top element out of contact therewith. The top member 115 is provided with a flange 117 which extends downwardly slightly below the top edge of the member 114. These members 114 and 115 are provided with mating die openings 118 for the passage of the punch 120. The strip 110 is somewhat wider than the die opening 118 so that the margins of the base strip are supported on the member 114 and on descent of the punch

120, a base element B of the shape shown in the upper portion of Figure 14 is punched from the strip 110. It will be noted that this element B has an extension 122 beyond the inner edge of the cap element A. Its top face is coated with an adhesive throughout its complete area, but this adhesive is not activated until such time as it is desired to use the corner mount and is then used to secure the mount in its position of use. The under face of the strip 10 is coated with an adhesive from the outer corner 123 of the base B substantially half way across, or to the dotted line 124 shown in Figure 14. Not only is this portion of the under face of the strip adhesive coated, but this coating activated before the strip 110 reaches its position beneath the punch. This activating means may comprise any suitable moistening device (not shown) located in its path of motion. Such a device, for example, is shown in the Riley Patent No. 1,627,667 granted May 10, 1927, for Machine for Making Corner Mounts, this machine, however, being employed to make a corner mount of different construction from that here illustrated.

The parts are so timed that on the retraction of the folder 50, leaving a folded cap element on the extremity of the presser plate 35, the punch 120 descends through the anvil block, punches a base member B therefrom and presents it with its activated adhesive coating against the folded-in corners 55 and 56 of the cap element A, thus uniting these parts to form the completed corner mount such as is shown in Figure 15. In order to insure proper presentation of the base element B as cut out by the punch, this punch 120 is shown as provided with a longitudinal passage 130 therethrough which, as shown best in Figure 1, may be connected through a flexible pipe or hose 131 with the upper portion of a cylinder 132 within which rides a plunger 133. This plunger 133 is secured to a bracket 143, which, in turn, is secured to the plunger 4, so that as the plunger 4 and the punch descends, the plunger 133 is partly withdrawn from the cylinder 132 thus creating a suction effect in the passage 130 which holds the punching against its under face and insures its correct presentation against the cap member. On lifting of the plunger 4, the suction effect is reversed so that the base member B is forcibly removed from the end of the punch.

The presentation of the punching or base member B in condition to adhere to the in-turned corners 55 and 56 of the cap A completes the formation of the corner element. It will be noted, however, that this corner element has been made up while the cap engages the end of the presser member 35. Means are therefore provided for ejecting this corner cap from the end of the presser member 35 after the base member has been applied. To this end, a slide 140 is mounted for sliding motion in a guide 141 carried by the table 1. This slide 140 has a backwardly directed flange 142 formed with a knife-shaped head 143 positioned at right angles to the length of the slide 140. This head 142 has a forwardly extended blade 144 at its outer end arranged generally parallel to the strip 10, and so positioned opposite to the punch opening 118 that as this plate element 144 is moved to the left as viewed in Figures 3 and 5, it will engage, wipe off and discharge from the presser plate 35 the completed corner. This

slide 140 is reciprocated at suitable times by the rotation of the shaft 39 which has fixed thereon a dog 150 (see Figure 5). As the shaft 139 rotates clockwise, the arm 150 engages on the rear face of a lug 151 upstanding from the member 140, so that as the shaft 139 continues to rotate, the dog 150 contacts that portion of the slide to force the slide to the left. After the dog 150 slips away from the lug 151, it contacts a face 152 of a dog 153 fulcrumed at 154, and rocks this dog 153 in counterclockwise direction, thus swinging its arm 155 in counterclockwise direction to impinge on the inner face of the slide lug 151. As the dog 153 continues to rock, it retracts this lug 151 and the ejector slide preparatory to another ejecting action. When the mounts are thus ejected, they are pushed into the upper end of a discharge passage 160 which leads down through the table 1 of the machine and to a suitable container (not shown).

In order to insure the ejection of the corners through the discharge passage 160, an air jet pipe 186 deriving compressed air from a suitable source leads down between the ejector knife blade 142 and the discharge passage 160 and a jet of air from this pipe discharged under control of a valve 1880 actuated by a cam 1861 on the shaft 39 blows the corners from the presser plate through the discharge passage 160. From this discharge passage 160, the corners as they are made pass out through a hood 187 and to the top face of a conveyor belt 182 (see Figure 2). This belt leads through the nip between a pair of pressure rolls 183 and 184 which serves to roll the cap and base of each mount together, insuring a good bond between them by the adhesive. The completed mounts on the belt then pass over a board 190 where they are discharged, the belt leading back over stretcher bars 191 and 192 and beneath the hood 187 where the corner mounts are deposited thereon. The presser rolls 183 and 184 are driven in time with the operation of the machine, as by a chain drive 195 driven by a belt 196 from a pulley on the shaft 6.

From the foregoing description of an embodiment of this invention, it should be evident to those skilled in the art that various changes and modifications might be made without departing from the spirit or scope of the invention.

I claim:

1. A machine of the class described, comprising means for feeding a relatively narrow cap strip endwise, an anvil across which said strip is fed and having a pair of angularly related upstanding edges both extending inwardly from the same side edge of said strip to the opposite side edge, a presser plate having an end tapered to mate the angularity of said upstanding edges; means for cutting off said cap strip at the front edge of said anvil and adjacent to one end of one only of said upstanding edges to form a cap element overlying said anvil, means pressing said plate toward said anvil to lift adjacent corners of said element for the full length of said element between said edges and said tapered end, a folding plate having a notch in its forward face, means for reciprocating said folding plate with its notched face across said presser plate to fold said lifted corners against said presser plate, and means for cutting and impressing on said folded corners a base element having an activated adhesive face to secure said cap and base elements together.

2. A machine of the class described, comprising

ing means for feeding a relatively narrow cap strip endwise, an anvil across which said strip is fed and having a pair of angularly related upstanding edges both extending inwardly from the same side edge of said strip, a presser plate having an end tapered to mate the angularity of said upstanding edges, means for cutting off said cap strip at the front edge of said anvil adjacent to one only of said upstanding edges to form a cap element overlying said anvil, means pressing said plate toward said anvil to lift adjacent corners of said cut element between said edges and said tapered end, a folding plate having a notch in its forward face, means for reciprocating said folding plate across said presser plate and laterally of said feed direction to cause said notched face to fold said lifted corners against said presser plate, means for cutting and impressing on said folded corners a base element extending beyond one side edge of said strip having an activated adhesive face to secure said cap and base elements together, and means for then freeing said cap element from said presser plate.

3. A machine of the class described, comprising means for feeding a relatively narrow cap strip endwise, an anvil across which said strip is fed and having a pair of angularly related upstanding edges extending inwardly from one edge of said strip, a presser plate having an end tapered to mate the angularity of said upstanding edges, means for cutting off said cap strip at the front edge of said anvil to form a cap element overlying said anvil, means pressing said plate toward said anvil to lift adjacent corners of said element between said edges and said tapered end, a folding plate, means for reciprocating said folding plate across said presser plate to fold said lifted corners against said presser plate, means for cutting and impressing on said folded corners a base element having an activated adhesive face to secure said cap and base elements together, a wiper, and means for reciprocating said wiper along said presser plate to free the completed corner mount therefrom.

4. A machine of the class described, comprising means for feeding a relatively narrow cap strip endwise, an anvil across which said strip is fed and having a pair of angularly related upstanding edges extending inwardly from one edge of said strip, a presser plate having an end tapered to mate the angularity of said upstanding edges, means for cutting off said cap strip at the front edge of said anvil to form a cap element overlying said anvil, means pressing said plate toward said anvil to lift adjacent corners of said cut element between said edges and said tapered end, a folding plate having a rectangular notch in its forward face, means for reciprocating said folding plate across said presser plate with one of said notch edges slightly in advance of the other and folding one of said corners in overlapping relation to the other corner to fold said lifted corners against said presser plate, and means for cutting and impressing on said folded corners a base element having an activated adhesive face to secure said cap and base elements together.

5. A machine of the class described, comprising a stationary anvil having a pair of angularly related upstanding edges at one side and a straight opposite edge, means for feeding a relatively narrow cap strip endwise across said anvil,

means for cutting off said strip at the front edge of said anvil adjacent to one only of said upstanding edges, a presser plate having an end tapered to mate the angularity of said upstanding edges, means pressing said plate toward said anvil to lift adjacent corners of said cut element between said edges and said tapered end, means for folding said corners over said presser plate to form a cap element, means for cutting and impressing on said folded corners a base element having an activated adhesive face to secure said cap and said base elements together, and means for ejecting said elements from said presser plate.

15 6. A machine of the class described, comprising a stationary anvil having a pair of angularly related upstanding edges at one side and a straight opposite edge, means for feeding a relatively narrow cap strip endwise across said anvil, means for cutting off said strip at the front edge of said anvil adjacent to one only of said upstanding edges, a presser plate having an end tapered to mate the angularity of said upstanding edges, means pressing said plate toward said anvil to lift adjacent corners of said cut element between said edges and said tapered end, means for folding said corners over said presser plate to form a cap element, means for cutting and impressing on said folded corners a base element having an activated adhesive face to secure said cap and said base elements together, and means reciprocating lengthwise of said cap strip for ejecting said elements from said presser plate.

35 7. A machine of the class described, comprising means for feeding a relatively narrow cap strip endwise, an anvil across which said strip is fed and having a pair of angularly related upstanding edges both extending inwardly from one side edge of said strip, a presser plate having an end tapered to mate the angularity of said upstanding edges, means for cutting off said cap strip at the front edge of said anvil adjacent to one only of said upstanding edges to form a cap element overlying said anvil, means pressing said plate toward said anvil to lift adjacent corners of said cut element between said edges and said tapered end, a folding plate having a notch in its forward face, means for reciprocating said folding plate laterally of the length of said strip across said presser plate to cause said notched face to fold said lifted corners against said presser plate into marginal lapping relation, a spring movable into the apex of said notch on retraction of said folding plate to insure dislodgement of a cap element therefrom at such retraction, and means for cutting and impressing on said folded corners a base element extending beyond the side edge of said cap and having an activated adhesive face to secure said cap and base elements together.

GEORGE STOKINGER.
